US0D1105056S

(12) **United States Design Patent** (10) **Patent No.:** **US D1,105,056 S**
(45) **Date of Patent:** **** Dec. 9, 2025**

(54) **PORTABLE COMPUTER**

(71) Applicant: **Guoping Long**, Honghu (CN)

(72) Inventor: **Guoping Long**, Honghu (CN)

(**) Term: **15 Years**

(21) Appl. No.: **29/997,081**

(22) Filed: **Apr. 4, 2025**

(51) LOC (15) Cl. **14-02**

(52) U.S. Cl.

USPC **D14/314**; D14/216

(58) **Field of Classification Search**

USPC D14/300, 301, 308, 314, 348, 349, 351,

D14/353-356, 364, 432, 439, 441,

D14/444-446, 172, 204, 209.1, 210-213,

D14/215, 216, 140-140.4, 240, 242, 125,

D14/203.1, 203.3, 203.6, 203.7, 496

CPC .. H05K 5/00; H05K 5/03; H05K 5/02; H05K

(57) **CLAIM**

The ornamental design for a portable computer as shown and described.

DESCRIPTION

FIG. 1 is a perspective view of a portable computer showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the portable computer that form no part of the claimed design.

1 Claim, 8 Drawing Sheets
